UNITED STATES PATENT OFFICE.

FRANK T. DICKSON, OF BALTIMORE, MARYLAND.

DESIGN FOR A WINDOW-CHAIR.

SPECIFICATION forming part of Design No. 32,011, dated December 19, 1899.

Application filed November 21, 1899. Serial No. 737,817. Term of patent 7 years.

To all whom it may concern:

Be it known that I, FRANK T. DICKSON, a citizen of the United States, residing at Baltimore, in the State of Maryland, have invented 5 and produced a new and original Design for Window-Chairs, of which the following is a specification.

The design consists of a flat base or seat *a*, having at one edge a downwardly-projecting 10 plate-flange *b* and at the opposite edge upwardly-projecting bars *d*, supporting a back-rest *c*. On the under side of the base or seat beneath the back-rest are two right-angle 15 braces *e*, each having one of its arms secured to said base, and the other arm projects down-

ward parallel with the said plate-flange *b*. The under side of the base or seat also has a cross-bar *f*, parallel with the plate-flange and between said plate-flange and the two right-angle braces *e*. 20

Having thus described my design, what I claim is—

The design for a window-chair as herein shown and described.

In testimony whereof I affix my signature 25 in the presence of two witnesses.

FRANK T. DICKSON.

Witnesses:

CHARLES B. MANN, Jr.,
CHARLES VIETSCH.
